BUCKET OPERATING MECHANISM

John B. Botten, Shaker Heights, Ohio

Application January 7, 1939, Serial No. 249,734

3 Claims. (Cl. 37—186)

This invention relates to mechanism for operating buckets of the clamshell, orange peel or like types.

One object of the invention is to provide simple and improved mechanism for operating the bucket in a manner to supply maximum power and to apply it most effectively, to increase digging ability and enable the bucket to work in harder or heavier material, and generally to simplify 10 and improve bucket operation and control.

A further object of the invention is to provide a self-contained device of this general type in which the power plant for opening and closing the bucket or grapple is carried by and incorporated in or as a part of the bucket itself, instead of being mounted on the hoisting machine with multiple line control extending to the bucket.

A further object of the invention is to provide improved bucket operating mechanism including a power motor, an operating drum and line, and a clutch connection between the two of suitable form to provide proper manipulation, and more particularly, bucket operating mechanism of the kind described mounted upon and forming part of the bucket itself.

Further objects of the invention are in part obvious and in part will appear more in detail hereinafter.

In the drawing, which represents one suitable embodiment of the invention, Fig. 1 is an end elevation, showing the bucket closed; Fig. 2 is a sectional elevation on approximately the line 2—2, Fig. 1, looking in the direction of the arrows; Fig. 3 is a sectional plan view on the line 3—3, Fig. 1, the gas tank and control device being omitted; Fig. 4 is a detail sectional elevation on the line 4—4, Fig. 2; Fig. 5 is a detail view illustrating the control devices for the power motor; and Fig. 6 is a diagram illustrating the application of a bucket, with its control devices, to a hoisting boom.

While the invention may be applied for operation of any form of opening and closing lifting or digging device or bucket, such as a grapple or a bucket of the orange peel type, said bucket may be of any form suitable for the purpose, the form, shape and arrangement of its parts forming no part of the present invention, except as claimed herein. For purposes of illustration and in no sense of limitation the invention has been shown applied to a clamshell bucket, including a head member 1, a counterweight member 2, bucket members 3, 4, links 5 by which the bucket members are suspended from the head 1, and links 6, 7 cross connecting the links 5 and the bucket members 3, 4, to harness the bucket members for uniform opening and closing movements, all as generally described and claimed in Letters Patent No. 2,007,704, granted July 9, 1935, to Henry W.

Botten for Bucket, to which patent reference may be had for a more complete description if desirable or necessary.

The operating mechanism for the bucket members is of any suitable form adapted to be carried entirely and supported by the bucket itself, so that it forms a part thereof, with suitable control devices of flexible form extending to the operating or control station on the ground or on the hoisting machine, according to the way in which the bucket is used. The power motor may be of any suitable form, such as an electric motor, but the drawing shows for the purpose an internal combustion engine conventionally represented at 8 and including a control device, such as the carburetor 9, supplied from a fuel tank 9a and having a throttle operating lever 10. The motor driven shaft 11 (Fig. 4) operates a clutch 12 by means of which power is transmitted to any suitable drum and cable winding means connecting the head member 1 and counterweight member 2 for operation, such as a Chinese windlass, generally marked 13, Fig. 2. This windlass is of well known form embodying a large drum 14 and a smaller drum 15, the opposite ends of a hoisting cable 16 being fastened to the two drums so as to be wound upon one when it is unwound from the other, said cable passing over a loose pulley 17 on a traveller 18 provided with rollers 19 by means of which it may move back and forth along a supporting rail 20 carried by the head member 1. As the driven shaft 21 (Fig. 4), which is attached to the drums of the Chinese windlass, is rotated in one direction or the other, the cable is paid off from one drum and onto the other with increase or reduction in the amount of free cable extending from the drums to the loose pulley 17, according to the direction in which shaft 21 is turned. This is the ordinary operation of a Chinese windlass, and by turning shaft 21 or permitting it to turn in one direction or the other, the counterweight 2 is permitted to descend, or may be raised, with relation to the head 1, causing the bucket members to open and close in the usual manner.

All parts of the power plant, including the power motor 8, the clutch 12, and the Chinese windlass drums 14, 15, are mounted upon or in and form a part of the counterweight 2, which includes a heavy box like sheet metal shell or casing 22 to house the several parts, which are securely fastened in said housing, and to which shell the bucket members 3, 4 are pivotally connected, as will be readily understood.

Clutch 12 may be of any suitable form, but a convenient form for the purpose is what is known as a hydraulic or liquid clutch, such as is illustrated in the issue of December, 1938, vol. 133, No. 6, pp. 63 to 65 inclusive of Popular Science, to which reference may be had for more com-

plete description of said clutch if necessary. The clutch is conventionally shown in the drawing as embodying two impellers, to-wit, a driving impeller 23 forming a part of the clutch 5 casing in which shaft 21 rotates, said impeller 23 being keyed to rotate with shaft 11. Within the casing is a driven impeller 24 mounted to rotate with and upon one end of the shaft 21. The two impellers are located opposite to each other, 10 as shown, and the space within the casing is filled with any suitable liquid, preferably somewhat viscous, such as a heavy oil, glycerine or the like.

A hydraulic or liquid clutch of this kind has the advantage that it requires no change speed 15 gears in the transmission line. When the motor or engine rotates at relatively low speed there is enough slippage in the clutch so that the driven shaft does not turn. That is the condition at idling speed of the engine, stopping of which is 20 thereby avoided, a desirable factor in the operation of internal combustion engines. As the speed of the engine is increased the driving liquid establishes more and more effective driving relation between the impellers 23, 24, driving impeller 24 25 and the driven shaft at increasing speed, until finally, at relatively high speed, when the acceleration load has been absorbed, the two impeller parts may rotate at almost the same speed.

For proper operation of this clutch in the bucket 30 operating mechanism described, any suitable means may be provided for controlling the motor 8 to drive it at three speeds, low, intermediate and high. As shown, throttle lever 18 has connected thereto the usual tension spring 25, which 35 normally tends to return it to the low speed or idling position. Attached to said arm by a link 26, is the core 27 of a two position electro-magnet or solenoid, including coils 28, 29. These coils are in circuit with a source of current 59 and a 40 controller generally indicated at 39, the operating arm 31 of which may be moved to any of three positions, marked respectively "dig," "hold" and "dump." In the dump position of the controller both coils 28, 29 are de-energized, the throttle 45 arm is in its idling position, and the engine is operating at its lowest speed. At that speed not only does the clutch 12 slip, but the permissible slippage is great enough so that the bucket can open of itself. That is to say, the gravity effect 50 of the counterweight is sufficient to cause it to move downward, thereby turning the Chinese windlass in the backward direction and rotating the driven impeller 24 in the opposite direction from the direction of rotation of the driving impeller 23.

By moving the controller to the "dig" position, coil 29 is energized and the throttle arm is moved over to its full speed position. The driven shaft and Chinese windlass are now driven in the forward direction with substantially full power transmission so as to close the bucket members and pick up and hold a load. When the bucket becomes fully closed full clutch slip is permitted, as is obvious.

When the controller handle is moved to the intermediate or "hold" position, coil 28 alone is energized, which moves the throttle arm to the intermediate position. In this position the engine operates at a speed which will just take care of the slippage of the clutch when it is subject to the opposing gravity effect of the bucket and any load it may contain. In other words, in this position of the throttle arm the bucket parts will be held in any given position, the motor counteracting

any tendency of the bucket to open, even under full load.

Fig. 6 illustrates application of the bucket to a hoisting mechanism including the usual pivoted boom 32. The bucket as a whole is supported from a hoist line 33, one end of which is fastened at 34 to the boom, said line extending around a loose pulley 35 attached to the bucket head, then around a pulley 36 on the boom, and then to the hoisting drum on the ground or on the hoisting machine. The control wires 37 extending between controller 30 and the throttle operating solenoid of course are flexible and will be led to the operating station for the hoisting mechanism. It will be observed that with this arrangement but a single line 33 is required, so that the hoisting mechanism is of simple form, and capable of operation by more or less unskilled operators, as compared with hoisting mechanism controlled by multiple lines, drums and clutches, and requiring skilled and expensive labor for efficient control and operation.

If desired, the motor 8, clutch 12 and winding mechanism 13 may be organized as a unit mounted for convenient attachment to and disconnection from the bucket, such as by so arranging the housing or shell 22 of the counterweight as to enable said unit to be inserted into the shell or removed from above, as will be readily understood.

Other advantages of the invention will be apparent to those skilled in the art.

What I claim is:

1. Apparatus of the class described, comprising a load lifting and carrying device, including head 35 and counterweight members, load holding parts operatively connected thereto and arranged to open and close upon relative motion of said members, and a power plant for operating said members mounted upon one thereof, said power plant 40 including a winding drum, a cable extending to the other member, an operating motor, and a liquid clutch between said motor and drum.

2. Apparatus of the class described, comprising a load lifting and carrying device, including head 45 and counterweight members, load holding parts operatively connected thereto and arranged to open and close upon relative motion of said members, and a power plant for operating said members mounted upon one thereof, said power plant 50 including a winding drum, a cable extending to the other member, a continuously operating unidirectional variable speed motor, a liquid clutch between said motor and winding drum, and means for controlling the speed of said motor, whereby 55 to produce bucket opening, closing or holding operations by the relation between clutch slippage and motor speed.

3. Apparatus of the class described, comprising a load lifting and carrying device, including head 60 and counterweight members, load holding parts operatively connected thereto and arranged to open and close upon relative motion of said members, and a power plant for operating said members mounted upon one thereof, said power 65 plant including a winding drum, a cable extending to the other member, an internal combustion engine, and a liquid clutch between said internal combustion engine and drum, whereby to produce bucket opening, closing or holding operations by 70 the relation between clutch slippage and the speed of said engine.

JOHN B. BOTTON.
